(57) **CLAIM**

I claim the ornamental design for a platform for work while standing, as shown and described.

DESCRIPTION

FIG. 1 is a perspective top view of a new design for a platform for work while standing;

FIG. 2 is a front view thereof; the rear view being a mirror image thereof;

FIG. 3 is a left side view thereof; the right side view being a mirror image thereof;

FIG. 4 is a bottom view thereof;

FIG. 5 is a top view thereof; and,

FIG. 6 is a perspective bottom view thereof.

The broken lines of the bumpers in FIGS. 2, 3, 4 and 6 are for the purpose of illustrating portions of the platform for work while standing and form no part of the claimed design. The large circle and pentagon shape shown on the bottom in FIGS. 2, 3, 4 and 6 represent claimed boundaries and form no part of the claimed design.
